UNITED STATES PATENT OFFICE.

H. CLAY BASCOM AND CYRUS A. HODGES, OF TROY, NEW YORK, ASSIGNORS
TO SAID BASCOM.

DESIGN FOR A COOKING-STOVE.

SPECIFICATION forming part of Design No. 15,401, dated September 16, 1884.

Application filed June 17, 1884. Term of patent 7 years.

To all whom it may concern:

Be it known that we, H. CLAY BASCOM and CYRUS A. HODGES, citizens of the United States, residing in the city of Troy, in the county of Rensselaer, and State of New York, have jointly invented and produced a new and original Design for Cooking-Stoves, of which the following is a specification, reference being had to the accompanying cut, print, or engraving representing our said new design.

This design embraces several new and distinct parts and combinations of parts, which go to make up the whole design, as shown in the accompanying illustration, and hereinafter specified.

The general shape of this design for cooking-stoves is not very materially different from that of some others heretofore produced.

One distinctive feature of this design is the shape and ornamentation of the front door, A, consisting of the main upper portion, B, having the plane border *a*, the ornamented surface *b*, curved convexly from top to bottom, and the draft-apertures *c*, with ornamental arched tops, and the smaller lower projecting part, C, having the ornamented name-band.

The oven-door D has the plane border *d*, raised panel-surface *l*, scroll-vine corner ornaments, *f*, angular corner ornament, *g*, sprig-ornament *h*, and connecting-ornaments *i*.

The design for the panel-plate E consists of the series of radial ornaments *j* in the plane surface *k*, having the sub-circular border *l*, with straight extended base part *l'*.

The design for the panels F and G consists of the border *m*, raised surface *n*, the scroll-vine corner ornaments, *o*, angular corner ornament, *o'*, and their connections, and the central ornament, *p*.

The design for the door H consists of the border *q*, raised surface *r*, corner ornaments, *s*,

s', with their connections, and the double ornament *t*.

The design for the legs I consists of the convexly and concavely curved surface *u*, the ornamental edgings *v*, and the compound scroll-vine and triangular ornament *w*.

The whole design embraces the shape and ornamentation of the top, the front, including the hearth and door A, the side, including the parts D, E, F, G, and H, and the legs.

We claim as new—

1. In a design for a stove, the shape and ornamentation of the front door, A, consisting of the parts B, *a*, *b*, *c*, and C, as set forth.

2. In a design for a stove, the shape and ornamentation of the oven-door D, consisting of the parts *d e f g h i*, as set forth.

3. In a design for a stove, the shape and ornamentation of the panel-plate E, consisting of the parts *j k l l'*, as shown and described.

4. In a design for a stove, the shape and ornamentation of the panels F and G, consisting of the parts *m n*, ornaments *o o'*, with their connections, and the part *p*, as set forth.

5. In a design for a stove, the shape and ornamentation of the door H, consisting of the parts *q r*, ornaments *s s'*, with their connections, and the part *t*, as set forth.

6. In a design for a stove, the shape and ornamentation of the legs, consisting of the parts *u v w*, as set forth.

7. The design for a stove, consisting of the top, front, side, and legs, shaped and ornamented as set forth.

In testimony whereof we hereunto set our hands, in the presence of two subscribing witnesses, this 14th day of June, 1884.

H. CLAY BASCOM.
CYRUS A. HODGES.
